WASHINGTON WALLICK, OF PHILADELPHIA, PENNSYLVANIA, ASSIGNOR
TO HIMSELF, S. F. PRINCE, AND H. K. SMITH, OF SAME PLACE.

Letters Patent No. 66,192, dated June 25, 1867.

IMPROVEMENT IN MACHINES FOR FEEDING NAIL-PLATES.

The Schedule referred to in these Letters Patent and making part of the same.

TO ALL WHOM IT MAY CONCERN:

Be it known that I, W. WALLICK, of Philadelphia, Pennsylvania, have invented an improved Machine for Feeding Nail-Plates; and I do hereby declare the following to be a full, clear, and exact description of the same, reference being had to the accompanying drawing, and to the letters of reference marked thereon.

My invention consists of certain mechanism fully described hereafter, by which nail-plates placed in a suitable receptacle are automatically withdrawn from the same and fed to a nail machine, thus dispensing with the services of an attendant.

In order to enable others skilled in the art to make and use my invention, I will now proceed to describe its construction and operation, reference being had to the accompanying drawing, which forms a part of this specification, and in which—

Figure 1 is a vertical section of my improved machine for feeding nail-plates.

Figure 2 is a transverse sectional view of the same.

Figure 3, a plan view.

Figure 4, the same, with the working parts in a different position.

Figure 5 is a sectional view on the line 1-2, fig. 2.

Figure 6 is a sectional view on the line 3-4, fig. 4.

Figures 7 and 8 are detached sectional views of parts of the machine; and

Figures 9 and 10, detached views drawn to an enlarged scale.

Similar letters refer to similar parts throughout the several views.

To the bed-plate A of the machine are secured the opposite side-frames B and B', connected by cross-pieces α , α' , and the main driving-shaft C turns in suitable bearings in the opposite side-frames, and in a standard, α'' , secured to the bed-plate. A sleeve, D, provided with a cog-wheel, b , is arranged to slide upon the square portion, c , of the shaft C, for a purpose described hereafter, (see fig. 2.) Between the side-frame A' and the standard α'' , and secured to the shaft C, is a cog-wheel, d , and an eccentric, e , the latter operating a pawl, e' , beneath which, and resting upon the bed-plate and frame A' of the machine, is a bar, f , having an inclined lower edge, f' , for a purpose described hereafter, (see figs. 5 and 8.) The bar f is connected to an arm, g , one end of which is pivoted to the cross-piece α of the machine, the other end being forked and entering a groove, g' , formed in the sleeve D of the driving-shaft. The pawl e' is adapted to the teeth of a ratchet-wheel, e'' , upon one end of a shaft, E, which turns in the opposite side-frames, and which is provided with two cog-wheels, h and h' , (see figs. 3 and 5.) The wheel h gears into the teeth of a rack, i , secured to the under side of a bed-plate F, which is arranged to slide in guides j , formed on the opposite side-frames A and A'. A large cog-wheel, G, gearing into the wheel d of the driving-shaft, is secured to a short spindle, k , which turns in bearings in the standard α'' and in a standard, k' , secured to the side-frame A. A rocking-plate, H, is arranged to vibrate in the brackets k , k' , and is provided with an arm, l , which enters a cam-groove, l' , formed on the inner face of the cog-wheel G, (fig. 5.) Extending along one edge of the plate H is a rounded projection, m , tapered at one end, as shown in figs. 3 and 4, and this portion of the plate enters a recess, m' , formed in a segmental pulley, I, which is secured to a spindle, n , turning in bearings p and p' on the bed-plate F. Two straps or flat chains, q and q' , are secured to the segmental pulley I, and connect the latter to a rock-spindle, J, one end of which turns in a rock-shaft, K, hung to the bearings p' and r (figs. 3 and 4.) A projection, s , of the shaft K, bears against the face s' of the spindle J, which is partly inclined, as will be seen on reference to figs. 9 and 10, and at the opposite side of the shaft K are two rounded projections or lugs, t and t' , and a pin, t' , passes through the spindle J, the object of which devices will be rendered apparent hereafter. The spindle J passes through a vertical slot, u , formed in a box on the bed-plate F, (fig. 7,) and is at this joint cranked, the cranked portion, v , turning in one end of an arm, v' , the other end of the said arm being hung to a stationary pin, v'' , all for a purpose described hereafter. The nippers L are hung to a pin, w , at the end of the spindle J, and the arms x of the said nippers are so connected by a spring, w' , that the jaws x' have a constant tendency to remain closed. A slot is cut in the spindle J for the reception of a plate, P, which is hung to a pin, y , and is of the peculiar shape shown in fig. 1. Projections, z , which are formed upon each side of the plate P, enter corresponding

recesses in the arms x of the nippers when the jaws of the latter are closed, as shown in fig. 4, and recesses 3 are also formed in the said plate for a purpose described hereafter. A lever, Q, is hung to a pin, 4, beneath the plate P, and its lower arm is forked, as shown in fig. 1, and embraces a pin, 5, at one end of a plate, R, which is arranged to vibrate upon a pin, 6. The plate R, at its lower end, is provided with two lugs, 7 and 7', and the side-frame A of the machine has a projection, 8, for a purpose described hereafter, (fig. 1.) Two brackets, S S, are secured to the side-frame A of the machine, in each of which, as shown in figs. 3 and 4, is formed a recess, 9, and a portion of a frame, T, which slides in guides formed on the brackets, is cut away, as shown in fig. 6, so as to present an abrupt shoulder, 10, and an opening, 11, is formed in each of the brackets for a purpose described hereafter. The forked arm of a bell-crank lever, U, which is hung to one of the brackets S, passes around a pin, 12, of the bed-plate F, and the short arm 13 of the said lever projects over the bed-plate F, on which is a block, V, having two lugs, 14 and 15, which will be referred to hereafter.

Operation.

The plates z, shown in red lines, figs. 1 and 3, and from which nails are to be made, are laid one upon another in the recesses 9 of the brackets S, which, together, form a box for their reception, and on reference to fig. 6 it will be seen that the bottom plate z' rests upon the frame T, and is in contact with the shoulder 10 of the same. Let it be supposed that the working parts of the machine are in the position shown in fig. 4, and let the red line Y represent the shears of a nail machine. Power is applied to the driving-shaft C, and is transmitted by the cog-wheels b and h' to the shaft E and cog-wheel h, and as this latter wheel gears into the rack i the sliding platform F is moved in the direction of the arrow 1, fig. 4. The bed-plate F continues moving, and the narrow lug 15 of the block V passes the arm 13 of the bell-crank lever U, which is struck by the lug 14 and moved so as to push out the frame T and bottom nail-plate z' to the position shown in fig. 3, or until the centre of the plate z' coincides with that of the spindle J, the segmental pulley I passing from contact with the projection m of the plate H, so as not to be operated by the latter. Owing to the arrangement of the arm v¹, the spindle J, and pins v v², the spindle, when resting upon the lower end of the slot u, will be so turned that the nippers will be in a vertical position, and the plate P will be in the proper position to be brought in contact with its operating devices. At the same time the lug 7, fig. 1, of the plate R, strikes the projection 8 of the side-frame A, the plate R is moved on its pin 6, and through the medium of the lever Q, the end of which enters one of the recesses 3 of the plate P, the latter is turned from its position, fig. 4, to that shown in fig. 1, thereby forcing open the jaws x' of the nippers L. Then, by means of any ordinary mechanism connected with the nail machine, the sleeve D of the shaft C is moved to the position shown in figs. 2 and 3, thereby throwing the cog-wheels b and h' out of gear, and the bar f, through the medium of the arm g, is moved from the position shown in dotted lines, fig. 8, to that shown in full lines, thereby causing the pawl e', fig. 5, to drop to the teeth of the ratchet-wheel e'' on the shaft E. As the shaft C continues to revolve the ratchet-wheel e'' is turned slowly by the pawl e', and through the medium of the cog-wheel h the bed-plate F is moved slowly in the direction of the arrows 2, figs. 1 and 3, until the jaws of the nippers L reach the end of the plate z'. Then the lug 7' of the plate R strikes the projection 8 of the side-frame and turns the plate P, as above described, when, by the action of the spring w', the jaws x' of the nippers are suddenly closed and the end of the plate z' is held securely between them. At the same time the lug 15 of the block V strikes the arm 13 of the bell-crank lever U, which is moved until the frame T is drawn back to its original position, leaving the plate z' between the jaws of the nippers. By means of the cam-groove l' of the cog-wheel G, fig. 5, a rocking motion is imparted to the plate H, and as the bed-plate F advances towards the same the tapered end of the projection m of the plate enters the recess m' of the segmental pulley I, to which the rocking motion of the plate is imparted. This motion of the pulley is transferred to the rock-spindle J by means of the straps q and q', the strap q turning the spindle when the segment is moved in one direction, and the strap q' turning the spindle in the opposite direction when the motion of the segment is reversed.

It should be understood that the machine is so arranged that this rocking motion of the spindle J never exceeds one-half of a revolution in either direction, thus insuring a uniform turning of the nail-plate z' as it is fed up, so that opposite flat sides of the same shall be alternately presented to the action of the shears of the nail machine. As the plate rests upon a table while being cut, it must be raised in order to be turned, and at the same time be drawn back a short distance to avoid striking the shears. The raising of the spindle and plate is effected by means of the cranked portion v of the spindle and the arm v¹, for the spindle J (fig. 7) is confined in the vertical slot u, and the cranked portion turns on the pin v; hence it must necessarily rise and fall when turned, its bearing in the rock-shaft K permitting such motion. When the spindle J is turned in the direction of its arrow, fig. 9, the pin t' strikes the rounded projections t t of the rock-shaft K, and as the pin is turned on them the spindle is drawn back to the position shown in fig. 10. When the motion of the spindle is reversed its inclined face s' comes in contact with and turns upon the projection s of the shaft K, by means of which the spindle is pushed forward to its original position, fig. 9. The forward motion of the bed-plate F is continued until all of the plate z', except the small portion held in the nippers, has been fed to the nail machine, when the cog-wheel b is again thrown into gear with the wheel h', and the bed-plate F is moved rapidly back. The reversing of the motion, as before described, operates the arm g, and the bar f is drawn back and raised by reason of its inclined edge f', as shown by dotted lines, fig. 8, thus withdrawing the pawl e' from the teeth of the ratchet-wheel e''. The backward motion of the platform is continued until another plate is pushed forward and the jaws of the nippers opened, when the motion is again reversed, the plate grasped, and the operation goes on as before.

I claim as my invention, and desire to secure by Letters Patent—

1. The nippers L, constructed substantially as described, in combination with the devices herein set forth,

or the equivalent to the same, whereby the reversing and reciprocating and vertical vibrating motion are imparted to the said nippers, as and for the purpose herein set forth.

2. The said nippers L, having the above-specified movements, in combination with a bed-plate, F, by which the nippers are carried, and with the devices herein described, or their equivalents, by which the said bed-plate and its nippers are advanced at uniform intervals, for the purpose described.

3. The recessed brackets S S, or their equivalents, for holding the strips to be converted into nails, in combination with the sliding-frame T and its shoulder, and the mechanism described, or its equivalent, for operating the frame and causing the latter to move the lowest of the strips within the range of the nippers, as set forth.

4. The nippers, constructed substantially as described, and connected to the spindle J, in combination with the cam-like plate P, hung to the said spindle, and operated by the moving bed-plate through the mechanism described, or its equivalent, so that the said plate P may open the jaws of the nippers and permit the same to be self-closed, in the manner and for the purpose specified.

5. The segmental pulley I, carried by the moving bed F, and arranged to operate the spindle J through the medium of straps q and q', or their equivalents, in combination with the vibrating-plate H and its pointed projection.

In testimony whereof I have signed my name to this specification in the presence of two subscribing witnesses.

WASHINGTON WALLICK.
